UNITED STATES PATENT OFFICE.

ALLEN A. BOWSER, OF FORT WAYNE, INDIANA, ASSIGNOR TO S. F. BOWSER & COMPANY, INCORPORATED, OF FORT WAYNE, INDIANA.

PUMP.

1,138,621.

Specification of Letters Patent.

Patented May 11, 1915.

Application filed November 4, 1912. Serial No. 729,251.

To all whom it may concern:

Be it known that I, ALLEN A. BOWSER, a citizen of the United States, residing at Fort Wayne, in the county of Allen and State of Indiana, have invented certain new and useful Improvements in Pumps, of which the following is a specification.

This invention relates to pumps, and more particularly to flow-back release mechanism 10 for pumps, and one of the principal objects of the invention is to provide means whereby the pump cylinder may be drained of its contents at any desired time.

A further object of the invention is to 15 provide means for actuating the flow-back release mechanism.

On the attainment of these ends, and the accomplishment of other new and useful objects, as will appear, the invention consists 20 in features of novelty in the construction, combination and arrangement of the several parts generally shown in the accompanying drawings and described in the specification, but more particularly pointed out in the ap- 25 pended claims.

In the drawings Figure 1 is a side elevation of the operating mechanism for a pump of the class described, constructed in accordance with the principles of my invention; Fig. 2 is a detail sectional view of an 30 adjustable stop; Fig. 3 is a view partly in elevation and partly in section of a pump cylinder provided with flow-back release mechanism; Fig. 4 is a perspective view of 35 one of the parts; Fig. 5 is a perspective view of another of the parts; Fig. 6 is a plan view showing the quantity registering mechanism; Fig. 7 is a sectional view taken along line 7-7 of Fig. 3; Fig. 8 is a side elevation 40 of a modified form of the operating mechanism; Fig. 9 is a detail view of some of the parts shown in Fig. 8.

In pumps which are employed for the purpose of discharging inflammable or combustible fluid, it is desirable to provide 45 means for permitting the fluid which may be contained in the pump cylinder at any time to return to a reservoir from which the fluid is pumped. This is particularly true of pumps for discharging gasolene, oil and the like, where the reservoir from which the fluid is pumped is located at a distance 50 from the pump itself for the purposes of safety and for meeting with the fire insur-

ance requirements. The present invention 55 is particularly designed and intended to accomplish this result.

Referring now more particularly to the drawings and in the present exemplification of the invention, a pump casing 10 of any desired or suitable construction is provided with a piston, reciprocable therein and having a piston rod 12 secured thereto and movable through a cap member 13 at one end of the cylinder. 65

The pump is of the type in which the piston is provided with a valve to admit the fluid pumped from one side of the piston through the piston during one stroke thereof to discharge the liquid during the opposite 70 stroke. For accomplishing this result the piston 11 is provided with packing rings 14 and packing members 15 of any desired or suitable construction and is formed with an opening 16 preferably adjacent to the center 75 thereof having a guide 17 thereon with the upper edges 18 of the opening forming a valve seat for a valve 19, the stem 20 of which extends through the guide 17, the valve being freely movable and operative to 80 open and close the passage through the piston. The piston 11 is also provided with a yoke 21 which extends upwardly over the opening 16 therein and forms a means of attachment for the end of the piston rod 12. 85 In the preferred construction the end of the piston rod 12 extends through the yoke 21, and is provided with a lock nut 43. A buffer 44 is also disposed at the end of the piston rod to limit the upward movement of the 90 valve 19 with respect to the piston.

At the end of the cylinder 10 opposite the cap member 13 is a chambered base member 22 having a laterally extending portion 23 which has an opening 24 therein. This opening 24 is an inlet opening for the fluid pumped and is disposed at the under side of the base member 22. Opposite the opening 24 and in the projecting portion 23 is an internally threaded opening 25, which is 100 adapted to be closed by means of a threaded cap member 26. Disposed within the extending portion 23 adjacent to the opening 24 is a valve seat 27 and mounted in the opening 25 in a suitable manner is a guide 105 28. This guide may be held in position by means of a shoulder 29 extending around the inside of the opening 25, the guide 28 being

of a diameter to engage the shoulder and to be held in place by the cap 26 when it is threaded into position. The valve 30 having a valve stem 31 which extends through the 5 guide 28 is adapted to be seated upon the valve seat 27 and the valve stem is provided with a shoulder 32 intermediate of the ends thereof.

Disposed in the chamber in the base member 22 is a support 33 in which a lever 34 is pivotally mounted. This lever is provided at one end with a knob 35 (see Fig. 4) and adjacent to the other end on both sides of the lever with projections 36. These projections 36 are formed with shoulders 37. The lever 34 is provided with an opening 38 adjacent the end upon which the projections 36 are located for a pivotally mounted dog 39. This dog as shown more clearly in Fig. 5 10 is preferably formed with perforated bifurcations having shoulders 40 therein extending in one direction and an engaging portion 41 extending in the opposite direction. When this dog is in position at the end of 15 the lever 34 the shoulders 40 of the dog are adapted to engage the shoulders 37 on the projections 36 of the lever to prevent the movement of the dog beyond a certain position with respect to the lever in one direction 20 but permitting a limited rotative movement in the other direction. The engaging portion 41 of the dog is adapted to extend beneath the shoulder 32 on the valve stem 31 of the valve 30 so that a downward movement 25 of the lever 34 at the end upon which the knob 35 is located will raise the valve 30 off of its seat 27. It is to be understood, of course, that the valve 30 is free to act in accordance with the movement of the piston 30. In order to maintain the lever 34 and the dog 39 in position so that the valve 30 will not be normally engaged thereby, a spring 42 is disposed between the knob 35 and the support 33 which tends to press this 40 end of the lever 34 upward.

In order to operate the lever 34 to raise the valve 30, the piston 11 is permitted to descend slowly below its normal position at the end of its stroke whereupon the end of 45 the valve stem 20 engages the knob 35 causing the valve 19 to be raised until it strikes the buffer 44 which causes the lever 34 to be depressed against the action of the spring 42, whereupon the valve 30 will be raised from its seat 27. It will be understood that during the normal operation of the pump the piston does not descend to a point where the end of the valve stem engages the knob 50 of the lever 34. In order to effect the operation of the lever 34 the piston rod 12 is provided with means for permitting an additional movement thereof at the end of the stroke. A suitable means for permitting the additional movement of the piston rod 55 12 at the lower end of its stroke is illus-

trated by Figs. 1 and 6. A rack 45 is secured to the piston rod 12 preferably at the upper end thereof and is formed with a projection 46 preferably disposed at the bottom of the rack. This rack is made adjustable 70 upon the rod by providing it with collars 47 at the ends thereof which surround the rod. One of the collars is provided with an adjustable screw 48 and the end of the rod 12 being provided with a cap nut 49. A pinion 75 50 mounted upon a shaft 51 meshes with the teeth of the rack and a gear 52 is mounted upon the same shaft 51, which meshes with a pinion 53. This pinion 53 is secured to a shaft 54 to which a hand crank 55 is also 80 secured. The rotation of the crank 55 causes the movement of the rack 45 in the well-known manner. In order to limit the movement of the rack so that any pre-determined amount of liquid may be pumped at a stroke 85 a threaded rod 56 having a longitudinally extending keyway 57 is mounted for free rotation about an axis parallel with the piston rod 12 and is provided with a number of adjustable stops 58, which are adapted to be 90 moved into position to engage the projection 46 of the rack 45 during its upward movement. These stops each preferably comprise a recessed member 59 (see Fig. 2) with openings 60 at right angles to the recess and having a key-way 61 in which a key 62 is disposed, the key having a projecting portion 63 which extends along the key-way 57 of the rod 56. An internally threaded member 64 with external notches 65 is disposed in 95 the recess of the member 59 and is threaded upon the rod 56, so that the rotation of the member 64 causes the longitudinal movement of the member 59, without rotating the latter. In order to maintain the threaded member 64 in any adjusted position the member 59 is provided with one or more perforations through which a pin 66 may be inserted in such a position as to engage in 100 one of the notches 65 of the member. To limit the normal movement of the rack 45 in the desired direction a stop device 67 is provided which is mounted upon the rod 56 and is preferably constructed and operated in the same manner as the stops 58, but is provided with an engaging portion 68, of greater angular width than the engaging portions of the stops 58, as shown more 105 clearly in Fig. 6.

The pump is preferably constructed with a tubular member 69 extending from the cap member 13 and supporting a frame 70, the frame having an upwardly extending portion 78, by which the operating mechanism is supported. One end of the rod 56 110 is preferably mounted for free rotation in the frame 70 and adjacent the upper face thereof, the rod 56 is provided with a collar 71 from which a finger or pointer 72 extends. Secured to the face of the frame 115 120 125 130 135 140 145 150 155 160 165 170 175 180

- 70 is a dial 73 which indicates several angular positions to which the arm or pointer 72 may be moved to position the rod 56. The stops 58 are arranged upon the rod 56 at 5 different angular positions than the arm or pointer whereby the rotation of the rod 56 by means of the pointer 72 will position one of the stops 58 to engage the projection 46 of the rack 45 during its upward movement.
- 10 The stop 67 limits the normal movement of the rack in the other direction as previously explained. When it is desired to operate the releasing mechanism at the bottom of the casing 10, the stop 67 must first be rotated by means of the arm or pointer 72 so 15 that the engaging surface 68 of the stop 67 will be cleared of the rack 45. To accomplish this result the pointer 72 must be moved to the position marked "Open" on the dial or plate 73. When the stop 67 has 20 been moved to this position the rack 45 and the piston rod 12 may be dropped or forced downwardly a slight distance sufficient to engage the end of the valve stem 20 (see 25 Fig. 3) with the knob 35 of the lever 34. Under these circumstances the valves 30 and 19 will be raised from their valve seats which will permit any liquid which happens to be in the pump casing 10 or in the chambered member 22 to flow downwardly 30 through the inlet opening 24 and thence to the supply tank or reservoir.
- If desired the discharge or tubular member 69 which is connected to the top of the 35 pump casing may be connected with a discharge pipe 74 which may be provided with a reservoir connection or stand pipe 75.
- A modified form of the operating mechanism is illustrated by Figs. 8 and 9, comprising a rack and operating mechanism similar to that already described but differing in the construction of the specific mechanism. A bar 76 is rotatably mounted in the pump frame in proximity to the rack 45 thereof and is provided with an arm or pointer 72 similar to that already described. A number of stops 77 are positioned upon the bar 76 and are each provided with an adjusting screw 78. These stops are rotated by means of the arm 72 into a position 50 to engage the projection 46 of the rack 45 as previously explained. Instead of providing a stop at the bottom of the rack, the top of the pump frame 78 is provided with 55 a forked member 79 which extends on both sides of the rack 45 as shown in Fig. 9. The top of the piston rod 12 is provided with a nut 80 having an enlarged flange 81 which is adapted to engage the forked member 79 to prevent the rack and piston rod 60 from moving downwardly a distance equal to the height of forked member 79. This member 79 is provided with a slotted portion 82 through the slot of which an adjusting nut 83 extends into a fixed portion
- of the support to hold the forked member 79 releasable in position. When the member 79 is withdrawn so that it is not engaged by the flange 80 the piston rod 12 will be permitted to drop an additional distance 70 which is sufficient to operate the flow-back releasing mechanism as previously set forth.
- While I have thus described the preferred embodiment of my invention it is evident that those skilled in the arts to which this 75 relates may make various changes in the construction, combination and arrangement of the several parts without departing from the spirit and scope of the invention.
- What I claim is:
1. The combination with a pump having a reciprocable piston, of an admission valve movable parallel with the piston but spaced laterally from the pump at the bottom, and a normally inoperative lever engaging both 80 the valve and piston to open the valve by a movement of the piston in one direction.
2. The combination with a pump having a reciprocable piston, of an admission valve movable parallel therewith but spaced laterally from the pump at the bottom, and a lever normally inoperative but adapted to engage both the valve and the piston when the piston is moved an additional distance 90 in one direction, for opening the valve. 95
3. In a pump, the combination with a reciprocable valved piston, of an admission valve at the bottom of the pump movable parallel with the piston but spaced therefrom, and a lever normally inoperative disposed at the bottom of the pump and adapted to be interposed between the valve in the piston and the other valve engaging both 100 valves when the piston is moved an additional distance in the downward direction. 105
4. In a pump, the combination with a reciprocable valved piston having an ordinary length of travel and capable of movement an additional distance in one direction, a movable stop to govern the additional movement of the piston, an admission valve at the bottom of the pump movable parallel with the piston but spaced laterally therefrom, a lever of the first order normally inoperative but adapted to be engaged by the 110 piston valve when the piston is moved an additional distance to open both the piston valve and the admission valve to permit a 115 back flow of fluid from within the pump.
5. In a lift pump, the combination with a 120 valved piston reciprocable therein, a stop on the piston to limit the opening movement of the valve, means to permit an additional movement of the piston at one end of its stroke, an admission valve for the pump 125 spaced from the piston but movable parallel therewith, a lever of the first order normally ineffective but adapted to be interposed between the valve in the piston and the admission valve and operated by engage- 130

- ment with the piston valve when the piston is moved an additional distance to raise both of said valves.
6. In a flow-back release mechanism for pumps, the combination with a piston having a valved opening therethrough, a valve for said opening with a stem extending below the piston, an inlet valve for the pump, a lever normally ineffective but operable to open the inlet valve when the valve in the piston is opened at the end of its stroke by engagement with the lever, and means to cause the piston valve stem to engage the lever at the end of the stroke of the piston.
- 10 7. In a flow-back release mechanism for pumps, the combination with a member having an inlet opening, and inwardly opening valve therefor, a pivoted lever having projections with shoulders therein, and a dog to engage the valve pivotally connected to the lever with shoulders to engage the shoulders of the said lever, whereby the rotation of the dog is permitted in one direction and the dog engages the valve to open it in the other direction.
- 15 8. In a flow-back release device for pumps, the combination with a chambered member, an inlet opening therein, a valve for said opening having an inwardly extending valve stem, a second opening in said member in the wall opposite the first named opening, and having an inner shoulder therein, a guide for said valve stem disposed in said second opening against the shoulder, a cap to bind the guard in position, and a lever having means to engage the valve stem and to permit the valve to be bodily removed from the second opening.
- 20 9. A flow-back release mechanism for pumps, comprising a valve piston with the stem of the valve extending through the piston, a pivoted lever adapted to be engaged at one end by the said valve stem when the piston is given an additional movement, means to permit the said additional movement of the piston, an inlet valve adapted to be engaged by said lever when the first named valve stem engages the lever at its other end, and means tending normally to hold the said lever out of engaging position with respect to the said inlet valve.
- 25 10. In a pump, the combination with a piston, of an inwardly opening valve in the piston having a stem extending below the piston, means without the pump for effecting an additional movement at the lower end of its stroke beyond the ordinary length of stroke, and a flow-back release mechanism actuated by the additional movement of the piston comprising a valve spaced from the piston, a lever normally ineffective but having one arm to engage the release valve, and another arm to engage the piston valve to open the piston valve when the piston is moved an additional distance.
- 30 11. The combination with a pump, having a valved piston therein, a piston rod secured thereto, a flow-back release mechanism, the said piston being ineffective to engage the said mechanism during the normal operation of said pump, means to effect an additional movement of this piston whereby the said mechanism may be operated at any desired time, comprising a member secured to the piston rod having a projection therefrom, means to reciprocate the piston and piston rod, an adjustable stop for determining the length of stroke of the piston, selective means to position the said stop whereby the length of stroke of the piston may be determined and an additional movement thereof obtained, and a dial to indicate the position of said stop.
- 35 12. In testimony whereof I have signed my name to this specification, in the presence of two subscribing witnesses, on this 30th day of October, A. D. 1912.
